CLAIM

We claim the ornamental design of a facemask, as shown and described.

DESCRIPTION

The file of this patent contains at least one photograph/drawing executed in color. Copies of this patent with color photographs/drawings will be provided by the office upon request and payment of the necessary fee.

FIG. 1 is a bottom view of a facemask according to a first disclosed embodiment.

FIG. 2 is a front view of the facemask according to the first disclosed embodiment.

FIG. 3 is an isometric view of the facemask according to the first disclosed embodiment.

FIG. 4 is a left side view of the facemask according to the first disclosed embodiment.

FIG. 5 is a rear view of the facemask according to the first disclosed embodiment.

FIG. 6 is a right side view of the facemask according to the first disclosed embodiment.

FIG. 7 is a top view of the facemask according to the first disclosed embodiment.

FIG. 8 is a rear view of the facemask according to a second disclosed embodiment.

FIG. 9 is a bottom view of the facemask according to the second disclosed embodiment.

FIG. 10 is a front view of the facemask according to the second disclosed embodiment.

FIG. 11 is a left side view of the facemask according to the second disclosed embodiment.

(Continued)

FIG. 12 is a first front perspective view of the facemask according to the second disclosed embodiment.
 FIG. 13 is a first rear perspective view of the facemask according to the second disclosed embodiment.
 FIG. 14 is a second rear perspective view of the facemask according to the second disclosed embodiment.
 FIG. 15 is a second front perspective view of the facemask according to the second disclosed embodiment.
 FIG. 16 is a top view of the facemask according to the second disclosed embodiment; and,
 FIG. 17 is third front perspective view of the facemask according to the second disclosed embodiment.
 The broken lines in the drawings depict portions of the face mask that form no part of the claimed design.
